UNITED STATES PATENT OFFICE.

PETER N. SHINE, OF DETROIT, MICHIGAN, ASSIGNOR OF ONE-HALF TO VINCENT BRUKLER, OF DETROIT, MICHIGAN.

RATCHET MECHANISM.

1,282,718.

Specification of Letters Patent. Patented Oct. 22, 1918.

Application filed May 13, 1918. Serial No. 234,126.

To all whom it may concern:

Be it known that I, PETER N. SHINE, a subject of the King of Hungary, residing at Detroit, in the county of Wayne and State of Michigan, have invented certain new and useful Improvements in Ratchet Mechanism, of which the following is a specification, reference being had therein to the accompanying drawings.

10 This invention relates to ratchet mechanism, and aims to provide a mechanism that may be advantageously used for raising and lowering a load, wherein the load is moved by a cable or flexible connection attached to 15 a drum and adapted to wind and unwind relative thereto. The ratchet mechanism has been designed for intermittently rotating the drum in either direction and safely control the movement of the load.

20 I attain the above results by a durable and mechanical construction which will be hereinafter described and then claimed, and reference will now be had to the drawing, wherein—

25 Figure 1 is a side elevation of the ratchet mechanism, partly broken away and partly in section, and

Fig. 2 is a plan of the same partly broken away and partly in section.

30 In the drawing, the reference numeral 1 denotes a suitable support and connected thereto by a bolt 2 and a nut 3 is a frame 4 that may be held against rotation by one or more screws 5 connecting the frame 4 to 35 the support 1, adjacent the bolt 2.

Rotatable on the bolt 2, within the frame 4, is a drum or flanged wheel 6 having a ratchet wheel 7 at one side thereof and a notched wheel 8 at the opposite side with 40 all of said wheels either integrally formed or connected for rotation together.

Loose on the bolt 2, in the frame 4, are the side arms 9 of a forked or bifurcated member 10 which is held by screws or other 45 fastening means 11 in the end of a handle or lever 12.

The forked member 10 has plunger ways 13 for plungers 14 and 15, the plunger 14 being adapted to engage the ratchet wheel 7, and the plunger 15 the notched wheel 8. Both of said plungers are encircled by coiled compression springs 16 within the plunger ways 13, and the inner ends of said plungers

are notched, as at 17, to receive a rotatable locking member 18 positioned transversely of the member 10 in the handle 12. The locking member 18 has been shown as holding the plungers 14 and 15 in retracted positions, and said locking member is cut away, as at 19, so as to provide clearance for the inner end of either plunger, depending upon the position of the rotatable locking member. This member is held against displacement by a small screw 20 having its head extending into an annular groove 21 in the locking member 18, and said locking member has a cross rod or handle 22 to facilitate rotation. The frame 4 has two extensions 23 and 24, the former supporting a pivoted spring pressed dog that normally engages the ratchet wheel 7 and prevents a clockwise movement of the same, as shown in Fig. 1. The spring pressed dog 25 has a finger piece 26 so that said dog may be shifted out of engagement with the ratchet wheel.

The extension 24 supports a spring pressed pivoted trip member 27 that is adjacent the notched wheel 8 and is adapted to engage in an opening or recess 28 in the end of the plunger 15 and automatically shift said plunger out of engagement with the notched wheel 8.

On the side of the frame 4 is a housing 29 for a spring pressed detent 30 adapted to be locked in a retracted position by a locking member 31, in the housing 29 and similar to the locking member 18. The spring pressed detent 30 is adapted to engage in a notch of the wheel 8 and said detent and the plunger 15 are beveled so that the detent may enter the same notch in which the plunger engages and gradually replace said plunger. To retract the spring pressed detent 30 at predetermined times, the side of the member 10 has a cam 33 that may be shifted in and out of a slot 34 in the housing 29, so as to engage and disengage the detent 30.

A cable 35 has been shown as attached to the drum 6 and assuming that the cable sustains a load that is to be raised or lowered, the operation of raising the load by the ratchet mechanism, is as follows:

The locking members 18 and 31 are adjusted to hold the plunger 15 and the detent

30 retracted, with the plunger 14 free to engage the ratchet wheel 7. The handle or lever 12 is then swung to the right, considering Fig. 1, the plunger 14 receding over the 5 teeth of the ratchet wheel to obtain a fresh grip and then by swinging the lever 12 back again, to the left, the ratchet wheel 7 is partially rotated, also the drum 6, causing the cable 37 to be wound on the drum. The 10 spring pressed dog 25 will hold the ratchet wheel until another grip is obtained, and during the oscillatory movements of the handle or lever 12, the strokes of the handle or lever are limited by the extensions 23 and 15 24 of the frame 4.

During this operation, the cam 33 may enter the slot 34 of the housing 29, but nothing is accomplished thereby.

Assuming that the cable 35 has been 20 wound upon the drum and it is now desired to lower the load, the locking member 31 is shifted to release the detent 30, so that said detent may engage in one of the notches of the wheel 8. The locking member 18 is also 25 shifted to hold the plunger 14 in a retracted position and release the plunger 15, it being necessary to release the detent 30 first of all so that the drum 6 will be prevented from accidentally rotating.

30 With the detent 30 holding the notched wheel 8 against accidental rotation, the handle or lever 12 is swung, as before, so that the end of the plunger 15, which engages in a notch of the wheel 8, may rotate 35 the wheel clockwise. As the handle or lever 12 is swung, the cam 33 moves out of the housing 29 and releases the detent 30, so that said detent may immediately engage in the notch of the wheel 8 as soon as the stroke of 40 the handle or lever 12 has been completed. Now, when the handle or lever 12 is retracted so that the plunger 15 may obtain a fresh grip on the notched wheel 8, the cam 33 enters the slot 34 of the housing 29 and retracts the detent 30. As the detent leaves 45 the notch of the wheel 8, the plunger 15 immediately enters the same and the notched wheel may be again partially rotated in a clockwise manner. It will be noted that at 50 the end of each operating stroke of the handle or lever 12, that the trip member 27 shifts the plunger 15 out of engagement with the notched wheel 8, so that the handle or lever may be retracted. In this manner, the 55 detent 30 and the plunger 15 coöperate in permitting the cable 29 to be intermittently unwound from the drum 6, and the plunger 14 coöperates with the dog 25 permitting of the cable 35 being wound on the drum. It is 60 therefore possible to manipulate extremely heavy loads with the ratchet mechanism, without any danger of any part thereof slipping.

One embodiment of my invention has been 65 illustrated, but it is to be understood that the

structural elements are susceptible to such variations and modifications as fall within the scope of the appended claims.

What I claim is:—

1. A ratchet mechanism comprising a 70 frame, a revoluble drum in said frame and to which a cable is adapted to be attached and wound and unwound relative to said drum, a ratchet wheel at one side of said drum, a notched wheel at the opposite side of said 75 drum, a handle oscillatory relative to said drum, a dog carried by said frame and normally engaging said ratchet wheel, a plunger carried by said handle and adapted to co-operate with said dog in partially rotating 80 said drum, a detent carried by said frame adapted to engage said notched wheel, a plunger carried by said handle adapted to engage said notched wheel, and means carried by said handle adapted to engage said detent 85 and retain said detent in a retracted position during the partial rotation of said notched wheel by the plunger of said handle.

2. A ratchet mechanism comprising a 90 frame, a revoluble drum therein, a ratchet wheel at one side of said drum, a notched wheel at the opposite side of said drum, a handle oscillatory relative to said drum, a plunger carried by said handle and adapted to engage said ratchet wheel for moving said 95 ratchet wheel counterclockwise, a plunger carried by said handle and adapted to engage said notched wheel for rotating said notched wheel clockwise, and means carried by said frame adapted for holding said 100 ratchet wheel and said notched wheel while said plungers obtain a fresh grip thereon.

3. A ratchet mechanism comprising a 105 frame, a revoluble drum in said frame, a ratchet wheel at one side of said drum, a notched wheel at the opposite side of said 110 drum, a handle oscillatory relative to said drum, a plunger in said handle adapted to engage said ratchet wheel and move said drum counterclockwise, a plunger in said handle adapted to engage said notched wheel and move said wheel clockwise, means carried by said frame adapted to hold said notched wheel while the plunger of said 115 handle engages said notched wheel, means carried by said frame adapted to automatically move the plunger out of engagement with said notched wheel, and means carried by said handle adapted to hold said plungers in retracted position so that said drum 120 may freely revolve.

4. A ratchet mechanism comprising a 125 frame, a revoluble drum in said frame, a notched wheel at one side of said drum, a handle oscillatory relative to said drum, means carried by said handle for moving said drum counterclockwise, a plunger carried by said handle adapted to engage said notched wheel and rotate said drum clockwise, and means carried by said frame adapt- 130

ed to hold said notched wheel while said plunger obtains a fresh grip thereon.

5. A ratchet mechanism comprising a frame, a drum revoluble in said frame, a ratchet wheel at one side of said drum, a notched wheel at the opposite side of said drum, a handle oscillatory relative to said drum, means carried by said handle and adapted to engage said ratchet wheel and 10 said notched wheel so that said drum may be intermittently rotated in opposite direc-

tions, and means carried by said frame adapted for holding said ratchet wheel and said notched wheel while the first mentioned means is obtaining a fresh grip.

15

In testimony whereof I affix my signature in the presence of two witnesses.

PETER N. SHINE.
